UNITED STATES PATENT OFFICE

JAMES BARELS, OF MILWAUKEE, WISCONSIN

CARBURETOR

Application filed December 1, 1926. Serial No. 151,918.

The carburetor to which this invention particularly relates comprises in general a vaporizing chamber, a heating chamber therefor whereby the liquid fuel is converted into substantially vapor form before passing through the mixing valve into a mixing chamber, there to be mixed with air in the proper proportions.

Another object is to provide a carburetor which is inherently self-cleaning, thereby preventing the accumulation of sediment or other deleterious matter on the surface of the radiator adjacent the vaporizing chamber.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a central vertical section through the carburetor and a float operated fuel valve therefor;

Figure 2 is a top plan, partly in section, of the carburetor;

Figure 3 is a horizontal section on line 3—3 of Figure 1;

Figure 4 is a transverse vertical section on line 4—4 of Figure 1;

Figure 5 is an enlarged central vertical section through the vaporizing chamber and self-cleaning apparatus therefor;

Figure 6 is a horizontal section on line 6—6 of Figure 5;

Figure 7 is a top plan of the mixing valve, and

Figure 8 is a bottom plan of the mixing valve and the cleaner.

The carburetor comprises an atomizing chamber or area 1, a heating chamber or ra-

diator 2 therefor, and a vapor outlet pipe or duct 3 extending from the atomizing chamber to a mixing valve 4 controlling the proportion of air to fuel vapor admitted to a mixing chamber 5, all of which are contained within a housing composed of an upper or cover section 6 and a lower or base section 7. The cover 6 may be fastened to the base 7 by any suitable means 6'.

The atomizing chamber 1 consists of the annular space between a radiator plate 8 associated with the heating chamber 2 and the bottom of a cone shaped cap 9.

The liquid fuel is admitted to the atomizing chamber under control of a float operated valve 10 located in a float chamber 11, and the fuel passes from the float chamber 11 to the atomizing chamber 1 through a duct or passageway 12.

The heating chamber 2 is arranged to be heated by the exhaust gases from the internal combustion engine with which the carburetor is associated. These exhaust gases may be admitted to the heating chamber through the heating medium inlet pipe 13, extending through the wall of the base 7 of the carburetor housing and terminating in the bottom of the cup shaped heating chamber 2. The exhaust vapors may be discharged from the heating chamber 2 through an outlet pipe or duct 14 extending from the bottom of the heating chamber 2 around the fuel duct 12 and through the lower wall of the base 7 of the carburetor housing.

The heating chamber 2 is spaced from the base 7 of the carburetor housing and is supported by a central stem 15. The radiator plate 8 having a central aperture is seated at its periphery on a shoulder in the outer wall of the heating chamber 2 so that its upper surface is flush with the upper edge of the heating chamber wall which may be peened over the edge of the plate to make a gas tight joint. A central tube 16 extends through the aperture of the radiator plate 8 and is screwed in the central stem 15 and is seated against a shoulder therein. The screwing home of the tube 16 onto its seat causes radiator plate 8 to be clamped between the hub 17 of the tube 16 and the upper end 100

of a collar or sleeve 18 surrounding the tube 16 and seated on the upper end of the central stem 15. Thus a gas tight joint is formed between the radiator plate 8 and the central tube 16.

5 The central supporting stem 15 is bored to receive an adjustable fuel tube 19 which extends up into the central tube 16. The lower end of this adjustable fuel tube 19 is

19 provided with a plurality of radially extending apertures 21 whereby liquid fuel admitted from the float chamber 11 through the duct 12 may find its way into and up through the adjustable fuel tube 19.

15 The lower end of the adjustable tube 19 is threaded, as at 22, so that the upper end of the fuel tube 19 may be adjusted vertically by turning a knurled head 23 on the lower end thereof. The tube 19 may be locked by 20 means of a lock nut 24.

Liquid fuel is admitted to the atomizing chamber 1 from the fuel tube 19 through a plurality of radially extending openings 25 in the hub 17 of the central supporting tube 25 16. The inner ends of these radially extending openings 25 communicate with the interior of the tube 16 and the outer ends thereof terminate in an annular space 26 between the outer periphery of the hub 17 and an inner 30 circumferential wall of the conical cap 9. This annular space 26 is immediately above the chamber 1 so that the liquid fuel passing through the openings 25 into the annular space 26 is admitted freely to the chamber 1 and passes outwardly therethrough and over the radiator plate 8.

The base of the conical cap 9 has a plurality of feet 27 which rest upon the radiator plate 8 and space the base of the cone shaped cap 40 9 therefrom, the thickness of the feet determining the depth of the chamber. The conical cap 9 is secured to the central supporting tube 16 by screws 29 carrying pins 29 which fit into a circumferential groove 30 in the 45 hub 17.

The rate at which liquid fuel passes from the fuel tube 19 into the chamber 1 is controlled by a needle valve 31 positioned in the upper end of the fuel tube 19 and fastened to 50 the mixing valve 4 so as to be supported thereby and to move therewith.

The normal opening between the needle valve 31 and the end of the fuel tube 19 is adjusted by varying the position of the tube 19 with respect to the needle valve by means of the adjusting pin 22. Normally the opening is such that when the engine is running at low speeds, fuel is admitted to the chamber at a rate sufficient for the needs of 55 the engine.

The mixing valve 4 is cone shaped and is provided with a central sleeve 32 to receive the upper end of the central supporting tube 16.

65 The mixing valve 4 is rotatable on the tube

16 and is locked to the cone shaped cap 9 by a key 9' or other suitable means so that the latter is rotatable therewith for purposes to be described more fully hereinafter.

The wall of the cone shaped mixing valve 70 4 is provided with a plurality of openings 33 shaped as shown in Figure 7. These openings enable the mixing valve 4 to be rotatable while the carburetor is in operation.

The upper end of the housing base 7 is circular and is provided with a flange 34 which insures the ready seating of the cover 6 on the base. The inner face of this flange 34 is tapered and is provided with a slight groove 34' therein, in which the case 35 of the mixing valve normally seats. The end of the ring extension 36 of the mixing valve 4 is spaced a slight distance from the inclined periphery of the outer wall of the heating chamber 2 when the mixing valve is in its normal position.

The relation of the inclination of the inner face of the flange 34 to that of the outer face of the ring extension 36 and of the taper of the periphery of the heating chamber wall 30 to the inner face of the ring extension 36 is such that as the mixing valve is raised the inner and outer annular passageways gradually increase in size but at different rates.

These annular passages form air passages 55 for air admitted to the carburetor. The primary air is admitted through the inner passage. Air is admitted through the outer passage direct to the mixing chamber 5. Thus the mixing valve 4 controls the primary air as well as the air admitted directly to the mixing chamber.

Air is admitted to the carburetor through an air inlet 37 extending through the wall of the housing base 7 and surrounding the heating medium inlet pipe 13. The air communicates with the space immediately below the heating chamber 2 and also with the space immediately below and surrounding the ring extension 36 of the mixing valve 4.

The funnel shaped space between the wall of the cone shaped cap 9 and the inner wall of the mixing valve 4 constitutes a passage for fuel from the vaporizing chamber 1 to the mixing valve.

During the operation of the carburetor the mixing valve 4 is adapted to move vertically on the centrally supporting tube 16 and thereby causes the metering needle 31 to vary the opening at the upper end of the fuel tube 19.

The upward movement of the mixing valve 4 is limited by several inwardly extending brackets or fins 38 on the housing cover 6.

The usual butterfly throttle valve 39 is provided in the opening through the upper end of the cover 6 of the carburetor housing. This throttle valve may be operated by means of a lever 40 connected therewith, and the 130

range of movement of this throttle valve may be determined by adjusting screws 41.

The carburetor may be fastened direct to the intake manifold of an explosive engine or to a connecting pipe thereto by means of an aperture flange 42 provided on the cover 6 of the vaporizer housing.

It has been found that the exhaust vapors admitted to the heating chamber 2 condense constantly and that minute particles of liquid are discharged through the outlet pipe 14.

In order to make use of these condensed vapors for the purpose of providing moisture in the air admitted to the carburetor means are provided for collecting these small particles of condenser vapors and for introducing the same into the air inlet 37.

For this purpose a tube 43 is screwed into the wall of the outlet pipe 14 and is seated against a shoulder therein. This tube 43 is provided with an aperture 44 registering with an aperture 45 in the wall of the outlet pipe 14. A pair of baffle plates 46 and 47 are arranged in the tube 43 to collect the condensed vapors, the lower baffle plate 47 being so positioned adjacent the aperture 44 that these small particles of liquid or condensed vapors may be introduced into the air inlet 30 or space within the base 7 of the vaporizer housing surrounding the central stem 15, the heating chamber 2 and the heating medium inlet and outlet pipes therefor.

A screen 48 is also arranged within the tube 43 and serves as a barrier for any flaming gases that may pass through the heating chamber 2 from the exhaust pipe of the explosive engine with which the carburetor is associated.

The float chamber 11 may be made separately and fastened to the carburetor housing so that when assembled they form a unit.

For this purpose a pair of ears or lugs 49 are formed integral with an apertured projection 50 of the float chamber 11, while an apertured boss 51 is provided on the outer wall of the carburetor housing base 7. Thus the float chamber 11 may be securely fastened to the carburetor by means of screws 52 extending through the lugs 49 and into engagement with the boss 51. The central apertures in the projection 50 and the boss are arranged to be in alinement to provide a passageway 12 for fuel from the float chamber 11 to the carburetor. A metallic double tapered bushing 53 slightly larger than the apertures cooperates with the apertured projection 50 and boss 51 to provide a fluid-tight joint between the carburetor housing and the float chamber 11.

As is usual in carburetor constructions, a float 54 maintains the liquid fuel at a substantially constant level in the fuel tube 19 from whence it is drawn by suction into the atomizing chamber. By reason of the atomiz-

ing chamber outlet being of considerable area, the fuel spreads in a thin film over the radiator plate where a considerable portion of the fuel is reduced to a vapor state by reason of its intimate contact with the heat applied to the plate.

The atomized fuel passes upwardly through the passage formed by the inner wall of the mixing valve and the cone member 9 and outwardly through openings 33, which by reason of their shape impart a rotary movement to the valve. As the suction within the mixing chamber is increased, the mixing valve is raised, permitting air to pass between the outer wall thereof and the carburetor casing as well as through the fuel passage way. The air and atomized fuel are thoroughly commingled in the mixing chamber and then pass outwardly to the intake manifold of the engine equipped with the carburetor.

What I claim as my invention is:

1. A carburetor for an internal combustion engine, comprising a casing; a heater in the casing and having a radiator plate, a substantially cone-shaped member mounted over the radiator plate with its base spaced therefrom to define a fuel chamber having a peripheral outlet, means for admitting fuel to said chamber at an intermediate point, a mixing chamber, a substantially cone-shaped mixing valve telescoped over said cone-shaped member with its inner wall spaced therefrom and its lower edge extended below said outlet so as to provide a duct communicating with the mixing chamber for fuel emitted from said fuel chamber, said valve being vertically movable inwardly of said casing and having an opening in its upper part, and an air supply communicating with the lower end of the valve, part of the air from said supply passing upwardly between the cone-shaped member and the valve to carry the fuel therethrough and part of the air passing directly into the mixing chamber between one wall of said valve and the casing.

2. In a carburetor, a thermal element having a radiating surface, an air duct, a fuel supply duct through the thermal element with its discharge end adjacent the radiating surface whereby fuel conducted through the duct is discharged onto the radiating surface, a superimposed spacing member cooperating with the radiating surface to produce a restricted vaporizing area for depressing and spreading the fuel to contact with the radiating surface, and a vacuum-actuated member carried by the first said member for controlling the flow of fuel and air through said ducts.

3. In a carburetor, a liquid fuel nozzle having radial delivery outlets formed between two members, a chamber surrounding said nozzle and receiving therein heated air,

130

a heat conducting element forming one of said members and one wall of said chamber, and said heat conducting element being adapted to heat the fuel as it passes outwardly of the nozzle and thereover.

5. In a carburetor, a heating chamber, a radiator plate heated from said chamber, a fuel tube passing through the plate and adapted to discharge fuel directly onto the plate, a cap mounted on the tube immediately above the plate to, with the plate, form a restricted fuel passage, and a valve surrounding the cap and having a part normally extending below the bottom thereof to regulate the air supply and forming a mixing chamber.

6. In a carburetor, a heating chamber, a radiator plate heated from said chamber, a fuel tube passing through the plate and adapted to discharge fuel directly onto the plate, a cap mounted on the tube immediately above the plate to, with the plate, form a restricted fuel passage, and a vertically movable valve surrounding the cap and having a part normally extending below the bottom thereof to regulate the air supply and forming a mixing chamber.

7. In a carburetor, a heating chamber, a radiator plate heated from said chamber, a fuel tube passing through the plate and adapted to discharge fuel directly onto the plate, a cap mounted on the tube immediately above the plate to, with the plate, form a restricted fuel passage, a vertically movable valve surrounding the cap and having a part normally extending below the bottom thereof to regulate the air supply and forming a mixing chamber, and a metering pin movable with said valve for regulating the fuel supply.

8. In a carburetor, a heating chamber, a radiator plate heated from said chamber, a fuel tube passing through the plate and adapted to discharge fuel directly onto the plate, a cap mounted on the tube immediately above the plate to form a restricted fuel passage, a movable valve surrounding the cap and having a part normally extending below the bottom thereof to regulate the air supply and forming a mixing chamber, said valve regulating the air supply according to the speed of the engine, and a metering pin in said tube and carried by the valve for regulating the fuel supply.

9. In a carburetor for use with an internal combustion engine, a central heating chamber, a valve seat surrounding the chamber and spaced from the adjacent walls thereof to form an annular passage, an air supply communicated with said annular passage, a hollow mixing valve, means mounting the mixing valve for axial movement over the heating chamber, said hollow mixing valve being engageable with the valve seat to divert all air passing through the annular passage into

the interior of the mixing valve, means for discharging heated fuel into the interior of the mixing valve to commingle with the air therein and form a combustible mixture which is drawn from the valve by the suction of the engine, the mixing valve being lifted from the seat and held suspended by the engine suction in a position depending upon the degree of suction, whereby air passing through the annular passage also passes over and around the mixing valve, and means whereby the position of the mixing valve governs the volumes of air passing into the interior and around the exterior of the mixing valve.

10. In a carburetor, a movable hollow member forming a mixing chamber, means for conducting fuel to the interior of the member, an air supply communicated with the interior of the member through a restricted passage the area of which depends upon the position of the movable member, said movable member having an outlet opening through which the mixed air and fuel passes, and means whereby additional air is supplied to the mixture as it leaves the outlet opening around the outside of the movable member upon movement thereof.

11. In a carburetor, a casing, a valve seat in the casing, a hollow conical member normally resting on the valve seat to divide the interior of the casing into separated chambers, means for communicating the interior of the hollow conical member with a fuel supply, an air supply communicating with one of said separated chambers and the interior of the hollow conical member to be mixed with the fuel therein and form a combustible mixture, the conical member having an outlet opening through which the combustible mixture passes into the other of said separated chambers, means mounting the hollow conical member for movement away from the valve seat to admit air to said other separated chamber to be mixed with the combustible mixture, and means whereby the movement of the hollow conical member simultaneously meters the volume of air passing to its interior and passing around the exterior thereof.

12. In a carburetor adapted for use with an internal combustion engine, a casing, a valve seat in the casing, a hollow conical member normally engaged with the valve seat and dividing the interior of the casing into an upper and a lower chamber, means for communicating the interior of the hollow conical member with a fuel supply, an air supply communicated with the lower chamber and with the interior of the hollow conical member through a restricted passage, whereby air is mixed with the fuel therein to form a combustible mixture, the hollow conical member having outlet openings in its apex through which the combustible mix-

ture is drawn into the upper chamber by the suction of the engine, means mounting the hollow conical member for axial and rotational movement whereby the suction of the engine raises the hollow conical member off of the valve seat, the shape of the outlet openings therein being such that the passage of the combustible mixture therethrough imparts rotation to the hollow conical member, and raising of the hollow conical member increasing the area of the restricted passage through which air is drawn into the interior of the conical member and also permitting air to be drawn into the upper chamber between it and the valve seat whereby the air passes through the hollow conical member and around it.

12. In a carburetor adapted for use with an internal combustion engine, a casing, a valve seat in the casing, a hollow conical member normally engaged with the valve seat to divide the interior of the casing into an upper and a lower chamber, means for communicating the interior of the hollow conical member with a fuel supply, an air supply communicated with the lower chamber and with the interior of the hollow conical member through a restricted passage, whereby air is mixed with the fuel therein to form a combustible mixture, the hollow conical member having outlet openings at its apex through which the combustible mixture is drawn into the upper chamber by the suction of the engine, means mounting the hollow conical member for axial and rotational movement whereby the suction of the engine raises the hollow conical member off of the valve seat, the shape of the outlet openings being such that the passage of the combustible mixture therethrough imparts rotation to the hollow conical member and raising of the hollow conical member increasing the area of the restricted passage through which air is drawn into its interior and also permitting air to be drawn into the upper chamber between it and the valve seat whereby the air passes through the hollow conical member and around it, and means whereby the air passing into the upper chamber around the hollow conical member partially offsets the tendency of the engine suction to lift said conical member whereby the same is maintained in a balanced position.

13. In a carburetor, a central member, a fuel supply extending through the central member and adapted to discharge fuel outwardly thereof, means for heating the fuel just prior to being discharged from the central member whereby the fuel issues from the central member as vapor, an air supply, an inverted cup shaped valve member surrounding the central member with its peripheral edge spaced therefrom to afford communication with the air supply and forming a mixing chamber into which the vaporized fuel is

discharged to be mixed with air from the air supply, to form a combustible mixture which is discharged through outlet openings in the inverted cup shaped valve member, means mounting the valve member for axial movement toward and away from the central member, means whereby movement of the valve member away from the central member increases the space between its peripheral edge and the central member to admit more air, means whereby said movement of the valve member admits more fuel to its interior, and means whereby said movement of the valve member communicates the exterior of the cup shaped member with the air supply whereby the air passes both through the valve member and around it.

14. A carburetor adapted for use with an internal combustion engine comprising a casing, a valve seat within the casing, a conical hollow valve member movable in the casing and normally engaging the valve seat, an air supply beneath the valve seat whereby the interior of the conical hollow valve is in communication with the air supply, a central member forming a heating chamber adjacent the valve seat and having its outer wall inclined inwardly and upwardly and spaced from the peripheral edge of the conical hollow valve member, a fuel supply extending through the central member and adapted to discharge fuel outwardly from the upper peripheral edge of the central member and into the conical valve member to be mixed with the air therein, the fuel being heated just prior to its discharge from the peripheral edge of the central member and the mixed air and fuel passing through outlet openings in the apex of the valve member, and means mounting the valve member for axial movement whereby the suction of the engine lifts the valve member from the valve seat moving its peripheral edge to increase the space between it and the adjacent inclined wall of the central member to admit more air to the interior of the valve member and admitting air around and over the valve member, the air passing over the outside surface of the valve member counter-acting the lifting force of the engine suction.

15. In a carburetor having an air chamber, a heating chamber adapted to receive exhaust gases part of which condense into moisture particles within the chamber, means for conducting the exhaust gases out of the heating chamber, and means for catching the particles of moisture as they pass through said conducting means and discharging them into the air chamber.

16. In a carburetor having an air chamber and a heating chamber adapted to receive exhaust gases part of which condense into moisture particles within the heating chamber, a discharge passage through which the exhaust gases are conducted out of the heating chamber.

ber, said discharge passage having an opening communicating with the air chamber, and baffles mounted in said passage for catching the particles of moisture in the exhaust gases to conduct them through said aperture and into the air chamber.

In testimony whereof, I hereunto affix my signature.

CERTIFICATE OF CORRECTION.

Patent No. 1,840,999.

Granted January 12, 1932, to

JAMES BARELS.

It is hereby certified that error appears in the printed specification of the above numbered patent requiring correction as follows: Page 4, line 46, claim 7, after the word "to" insert the commas and words, with the plate,; and that the said Letters Patent should be read with this correction therein that the same may conform to the record of the case in the Patent Office.

Signed and sealed this 23rd day of February, A. D. 1932.
